Attorney

UNITED STATES PATENT OFFICE.

SIDNEY C. VINCENT, OF BALTIMORE, MARYLAND.

UMBRELLA.

Application filed April 12, 1922. Serial No. 551,786.

To all whom it may concern:

Be it known that SIDNEY C. VINCENT, citizen of United States, residing at Baltimore city, in the State of Maryland, has invented certain new and useful Improvements in Umbrellas, of which the following is a specification.

This invention relates to improvements in umbrellas.

- 10 The object of the invention is to so construct an umbrella with regard to simplicity and cheapness that it will be available for emergency use, either as a parasol or umbrella, that is to say, an article that will be 15 available at a nominal price, and one which will serve both as a protection against rain and sun, as for instance, when a person is caught in a sudden rain storm, or a situation in which a sun shade is required.
- 20 A further object of the invention is to produce an umbrella or parasol of the character above indicated which will serve the emergency purposes above mentioned, and which will at the same time possess durable 25 characteristics even beyond those required for such an article.

A still further object of the invention is to so construct the umbrella that it may be folded in compact form, either for carrying 30 or shipment.

Other objects and advantages will become apparent from the following description.

In my construction I simplify the umbrella greatly and cheapen its cost of manufacture by dispensing entirely with the usual brace portion of the ribs, and so construct the spreader that it serves both to spread the radial ribs, and at the same time serves as a means for locking their lower 40 ends in compact space in parallelism with the umbrella rod when the umbrella is folded.

In the drawings illustrating the invention:

45 Fig. 1 is a central sectional view of the umbrella or parasol raised.

Fig. 2 is a similar view showing the umbrella folded.

50 Fig. 3 is a top plan view and partial section of the sliding rod carrier.

Fig. 4 is a cross section taken about on line 4—4 of Fig. 2, showing the manner of confining the lower ends of the ribs in cup-shaped part of the spreader.

55 Fig. 5 is a sectional view of a modified form of rib carrier, there being shown in

position therein the inner ends of the two ribs.

Referring to the drawings, the numeral 1 designates the umbrella rod, to which is secured near its upper end a stationary rib carrier 2. This is circular and formed with a downwardly extending hub or sleeve 3, the whole carrier being provided with an aperture 4 for the passage of the rod 1. Radially arranged in the carrier are a number of kerfs 5 which receive the inner ends of the ribs 6, and the carrier is provided with an annular groove 7 for the reception of a wire 8 that is threaded through the ends of all of the ribs, whereby the ribs are held pivotally within the carrier. Covering the ribs and supported thereby is a canopy 9, which extends from the rod 1 to a point a little short of the outer ends of the ribs as shown in Fig. 1.

The numeral 10 designates a cap hollowed out slightly as indicated at 11 at its underside to permit the easy folding and movement of the upper ends of the ribs in the folding operation. Interposed between the cap and the upper edges of the ribs is a disk 12, which may be made of any suitable material, but preferably of the same material of which the canopy is made, and this is for the purpose of preventing the water, where the umbrella is used as a protection against rain, from trickling or leaking down the rod. This purpose is also augmented by the cap 10. This cap is secured to the rod in any suitable manner, but preferably by a short pin 13 that prevents the cap from moving upwardly on the rod, and the lower edge of the cap or flange thereof is designed to bear upon the upper edges of all of the ribs simultaneously when the umbrella is opened, and this contact, together with the action of the spreader which will now be described, prevents the ribs from passing above a horizontal line, and thereby together with the canopy effectually prevents the umbrella from turning wrong side out.

The numeral 14 designates the spreader, which is recessed as indicated at 15, and intersecting this recess is another recess 16 of smaller diameter than the recess 15, and the whole spreader is provided with an aperture 17 for the passage of the umbrella rod. The recess 16, as shown in Fig. 1, receives the sleeve of the rib holder when the umbrella is extended, thus presenting a tem-

porary cooperation sufficiently rigid for the purposes intended, and the recess 15, as shown in Figures 2 and 4, receive and confine the lower ends of the ribs when the umbrella 5 is folded. When the umbrella is raised, it will be noted that the outer edge or flange of the spreader engages simultaneously the under edges of all of the ribs at a point some distance beyond their pivots, and 10 as before intimated, when the umbrella is in raised position, or in the position shown in Fig. 1, the ribs are tightly held between the lower edge of the flange of the cap 10, and the upper edge of the flange of 15 the spreader, thus bringing about a rigidity suitable for the purpose intended. The rod near its top is provided with the usual spring catch 18, which is so positioned that when the spreader is raised to its full 20 extent, the upper edge of the catch will maintain it in such position, and similarly the lower part of the rod is provided with a catch 19, which is so positioned that when the spreader is at the lower part of the rod, 25 it will hold said rod in position to receive and confine the lower ends of all of the ribs, as shown in Fig. 4.

In letting down or folding the umbrella, the catch 19 is depressed so that the spreader 30 can come to a position slightly below the position shown in Fig. 2 to permit the ends of the ribs to be folded in and brought to position to be confined within the recess 15 of the spreader when the spreader is again 35 moved slightly upward until the catch rests against its lower end, as shown in Fig. 2.

In the modification shown in Fig. 5, the numeral 20 designates the rib holder provided with a number of radial recesses 21, 40 and this rib holder is provided with an aperture 22 for the passage of the rod. It is also provided with an annular groove 23 for the passage of the wire 8 which forms the pivot for the slightly modified ribs 24. In 45 this construction the inner ends of the ribs are squared as indicated at 25 for engagement with the outside of the hub or sleeve 26 when the umbrella is raised, this engagement being for the purpose of preventing 50 the ribs from being raised above a horizontal line drawn through the pivotal points for the purpose of preventing the umbrella from turning wrong side out. To enable the ribs to be folded down against the rod, they are 55 slightly rounded as indicated at 27.

In operation to unfold the umbrella it is only necessary to press the catch 19, which will permit the spreader to be moved down-

ward, slightly upon the handle. This will release all of the ends of the ribs simultaneously. The spreader is then forced up between the ribs to the position shown in Fig. 1, and following up the lower edges of the ribs they will be rocked upon their pivots until their upper edges engage the lower 65 edge of the flange of the cap 10, at which time the catch 18 will have come below the bottom of the spreader holding the parts in the position shown.

As before intimated this umbrella or parasol is intended primarily for temporary use, and the material used in its construction, may be any material suitable for the purpose, as for instance, the ribs may be made of wood, and the canopy may be made of 70 paraffined or treated paper, that is to say, a paper treated in such a way as to render it waterproof, and at the same time not interfere to any appreciable extent with its flexibility, and such material will have 75 sufficient durability to serve for the purpose intended.

Claims.

1. In an umbrella, in combination, a rod, a hollow cap secured to the upper part of said rod, a carrier secured to the upper part of the rod below the cap, a plurality of ribs having their inner ends pivoted in said carrier, said carrier being formed with a downwardly extending central portion embracing the rod, a spreader slidable on the rod and having a recess therein to receive the lower end of the central portion of the carrier when the spreader is in its uppermost position, and means for locking the spreader in such position.

2. In an umbrella, in combination, a rod, a hollow cap secured to the upper part of the rod, a carrier slidable on the rod, ribs pivoted in said carrier, the carrier being provided with a downwardly extending central portion embracing the rod, a spreader slidable on the rod, and of less diameter than the cap and provided with a central recess adapted when the spreader is in uppermost position to receive the lower end of the central portion of the carrier, and means for locking the spreader and consequently the ribs in uppermost position.

In testimony whereof I affix my signature 110 in presence of two witnesses,

SIDNEY C. VINCENT.
